UNITED STATES PATENT OFFICE.

ULYSSES S. AVERY, OF ASHLAND, KANSAS, ASSIGNOR OF ONE-HALF TO JEROME W. BERRYMAN, OF ASHLAND, KANSAS.

SCREEN.

1,073,016.

Specification of Letters Patent. Patented Sept. 9, 1913.

Application filed February 7, 1913. Serial No. 746,893.

To all whom it may concern:

Be it known that I, ULYSSES S. AVERY, a citizen of the United States, residing at Ashland, in the county of Clark and State of Kansas, have invented new and useful Improvements in Screens, of which the following is a specification.

The invention relates to screens and more particularly to screens for use on door and window casings and has for an object to provide a screen of simple and durable construction and which will present a neat and effective appearance.

The invention embodies among other features the use of the screen frame of the usual construction and upon which the screen wire is placed with metallic mold strips for connection with the screen frame and adapted to cover the edges of the screen and retain the screen rigidly on the frame, said metallic mold strips being shaped to present a neat and effective appearance when applied to the screen frame.

In the further disclosure of the invention reference is to be had to the accompanying drawings, constituting a part of this specification, in which similar characters of reference denote corresponding parts in all the views, and in which:

Figure 1 is a fragmentary perspective view of the completed screen; Fig. 2 is a transverse sectional view on the line 2—2 in Fig. 1; Fig. 3 is a longitudinal sectional view on the line 3—3 in Fig. 1; and Fig. 4 is a fragmentary perspective view of one of the mold strips.

Referring more particularly to the views, I disclose a screen 10 consisting of the usual rectangular screen frame 11 provided with a continuous recess 12 in which are received the ends of the usual screen wire 13, the screen being applied to the screen frame 11 in the usual manner as shown. Mold strips 14 are adapted for connection with the screen frame 11 to rigidly secure the wire 13 thereto and each of the said mold strips consists of a metallic body 15 preferably stamped or pressed from sheet metal and having a medial longitudinally extending bulging portion 16 as shown, thus providing parallel longitudinal strips or members 17 on both sides of the bulging portion 16, triangular shaped openings 18 being formed in the strip members 17 by stamping out triangular shaped pieces 19 from the strip members 17 the said pieces 19 projecting downwardly

beneath the openings 18 formed when the pieces 19 are struck from the strip members. In constructing the mold strips 14, a series of serrations 20 are formed on the under sides of the strip members 17 as shown, the said serrations being preferably pointed for a purpose that will be hereinafter more fully discussed.

The mold strips 14 are applied to the screen frame 11 in the manner disclosed in the figures, so that the strip members 17 will repose in the continuous recess 12 in the screen frame 11 and cover the edges of the screen wire 13, after which suitable tacks 21 are driven transversely through the openings 18 and the screen wire 13 with the pointed ends of the tacks extending into the screen frame 11 thus not only rigidly securing the screen wire to the frame, but also securing the mold strips 14 rigidly on the frame. Referring to Figs. 2 and 3 it will be seen that when the tacks 21 are driven into the screen frame in the manner mentioned, the depending angular pieces 19 will abut against the tacks, thus aiding in securing the tacks in position to accomplish the purposes for which they are provided. It will be further seen that when the screen 10 is completed, the strip members 17 will lie flush with the upper face of the screen frame and by providing the medial longitudinally extending bulging portion 16, the mold strips 14 will be given additional strength and will furthermore present a neat and effective appearance. In order to prevent the screen wire from tearing away from between the screen frame 11 and the mold strips 14, the serrations 20 are provided to project from the under sides of the strip members 17, the said serrations being adapted to engage and project through the mesh of the screen wire and extend into the screen frame 11 thus greatly increasing the securing area of the mold strips 14.

Having thus described my invention, I claim:

In a screen the combination with a screen frame adapted to receive and support the screen wire of mold strips for securing the screen wire on the frame, each of the said mold strips consisting of a single body having a medial longitudinally extending bulging portion and parallel strip members provided with openings adapted to receive fastening members therethrough to secure the mold strips on the said screen frame and

retain the screen wire thereon, and serrations formed on the under sides of the strip members and adapted to project through the screen wire and into the said screen frame 5 and further secure the screen wire on the frame.

In testimony whereof I affix my signature in presence of two witnesses.

ULYSSES S. AVERY.

Witnesses:
